UNITED STATES PATENT OFFICE.

JULIUS STEINER, OF WEST NEW YORK, NEW JERSEY, ASSIGNOR OF ONE-HALF TO
R. DALLA ROVERE, A PARTNERSHIP, OF WOODCLIFF, NEW JERSEY, COMPOSED OF RICHARD DALLA ROVERE AND ALFRED PRETROBELL.

DESIGN FOR A HAND BAG.

Application filed November 7, 1925. Serial No. 15,377. Term of patent 3½ years.

To all whom it may concern:

Be it known that I, JULIUS STEINER, a citizen of Switzerland, residing at West New York, county of Hudson, and State of New Jersey, have invented a new, original, and ornamental Design for Hand Bags, of which the following is a specification, reference being had to the accompanying drawing, forming part thereof.

The figure is a perspective view of a hand-bag showing my new design.

I claim:—

The ornamental design for a hand-bag as shown.

JULIUS STEINER.
